UNITED STATES PATENT OFFICE.

BENJAMIN CHAMPLIN, OF CORTLAND, ILLINOIS.

VETERINARY INSTRUMENT.

SPECIFICATION forming part of Letters Patent No. 404,074, dated May 28, 1889.

Application filed February 19, 1889. Serial No. 300,403. (No model.)

To all whom it may concern:

Be it known that I, BENJAMIN CHAMPLIN, of Cortland, in the county of De Kalb and State of Illinois, have invented a new and Improved Surgical Instrument, of which the following is a full, clear, and exact description.

Reference is to be had to the accompanying drawings, forming a part of this specification, in which similar letters of reference indicate corresponding parts in all the figures.

Figure 1 is a side elevation, partly in section, of my improved surgical instrument; and Fig. 2 is an edge view.

The object of my invention is to provide an instrument for opening the ducts of cows' teats which have been stopped by an obstruction or by a stricture.

My invention consists of a lance provided with a rounded tip and having shoulders near the tip for engaging the obstruction, the said lance being mounted on a suitable handle.

The lance A, which is formed of steel hardened and tempered in the usual way, is provided with a rounded head, *a*, having shoul-

ders *b* projecting a small distance beyond the sides of the lance. The cutting portion of the lance is made tapering, as shown, with two cutting-edges, *c c*. The shank *d* of the lance is provided with a tang, *e*, for insertion in the handle B.

The lance is used by inserting the rounded point into the duct of the teat and forcing the lance inward as far as necessary; then withdrawing it. I have found in practice that this treatment effectually cures all strictures of the ducts of the teats and is a permanent remedy of hard milking.

Having thus fully described my invention, I claim as new and desire to secure by Letters Patent—

An improved surgical instrument, consisting of a lance provided with a rounded head having shoulders projecting beyond the sides of the lance, substantially as specified.

BENJAMIN CHAMPLIN.
